DESIGN FOR A COSTUMER

Charles Eugene Stephenson, New York, N. Y.

Application March 5, 1946, Serial No. 127,115

Term of patent 7 years

(Cl. D33—8)

To all whom it may concern:

Be it known that I, Charles Eugene Stephenson, a citizen of the United States of America, residing in New York, in the county of New York and State of New York, have invented a new, original, and ornamental Design for a Costumer, of which the following is a specification, reference being had to the accompanying drawing, forming a part hereof.

I claim:

The ornamental design for a costumer, as shown.

CHARLES EUGENE STEPHENSON.
